(57) **CLAIM**

The ornamental design for a removable floor anchor, as shown and described.

DESCRIPTION

FIG. 1 is a front view of the removable floor anchor;
FIG. 2 is a left side view of the removable floor anchor;
FIG. 3 is a right side of the removable floor anchor;
FIG. 4 is a rear view of the removable floor anchor;
FIG. 5 is a top view of the removable floor anchor;
FIG. 6 is a bottom view of the removable floor anchor;
FIG. 7 is a perspective view of the removable floor anchor; and,
FIG. 8 is an environmental side view of the removable floor anchor in use.
The broken lines represent environment and form no part of the claimed design.
